UNITED STATES PATENT OFFICE

JOSEPH R. RUSSELL, OF CHICAGO, ILLINOIS.

BURNER FOR LIQUID FUEL.

No. 814,396.

Specification of Letters Patent.

Patented March 6, 1906.

Application filed May 22, 1905. Serial No. 261,520.

To all whom it may concern:

Be it known that I, JOSEPH R. RUSSELL, a citizen of the United States, and a resident of Chicago, in the county of Cook and State of Illinois, have invented a new and useful Improvement in Burners for Liquid Fuel, of which the following is a complete specification.

This invention is designed with reference to the consumption of hydrocarbon oils in furnaces used for welding, brazing, or other like purposes in which a high heat is required.

The object in view is to provide a burner simple in construction and efficient in operation and one in which the flame can be easily regulated not only in volume, but to suit the distance of the work from the burner and in variable amounts to any desired portion or side of the furnace.

Other subordinate improvements will be set forth in the following description and related in the appended claims.

The preferred construction of the improvement is illustrated in the accompanying drawings, in which—

Figure 1 represents a side elevation, partly in section, of a burner embodying my invention. Fig. 2 is an elevation of the burner as viewed from the left-hand side of Fig. 1. Fig. 3 is a plan section taken as indicated by the line 3 3 in Fig. 1. Fig. 4 represents a modification of the cone-stem and bearing for same, the modification consisting in providing an eccentric bearing for the said cone-stem, and thereby increasing the latitude of adjustment of the cone; and Fig. 5 is a diagrammatic view illustrating different positions to which the cone has been moved by the offset stem alone, the eccentric sleeve alone, and by the combined movement of both.

Referring to the drawings, 1 designates the body of the burner, which forms the mixing-chamber, although, strictly speaking, the mixing occurs below the oil-inlet. The air-inlet is at 2 and the discharge-opening at 3, the air following along the course indicated by the arrows. The air may be supplied under the required degree of pressure from any suitable source, the flange 4 affording connecting means with the supply-pipe. The lower end of the burner, or that portion below the flange 5, is designed to connect with the furnace immediately over the fire-pot, the said flange 5 affording the connecting means

therewith. The discharge-opening 3 is circular in transverse cross-section, as shown in Fig. 3, and truncatedly conical in vertical section, as shown in Fig. 1. A cone 6 is supported in the discharge-opening 3 by means of the vertically-extending stem 7, to the upper end of which is secured the hand-wheel 7² for turning said stem. The stem is threaded at its upper end and is received by a correspondingly-threaded boss 8, integral with the upper end of the burner-body. A supplementary stem-support 9 is provided intermediate of the length of said stem, as clearly illustrated in Fig. 1. Below the stem-support 9 an offset 7¹ is formed in the cone-stem 7, this offset enabling the cone to be moved to various positions in the discharge-outlet. This feature is of great importance, since in operation it is frequently, in fact almost constantly, desired to heat a certain portion of the furnace or the work more intensely at one place than another. By the movement of the cone through the offset stem or equivalent means the size of the opening on the side requiring a high heat can be enlarged or diminished at the will of the operator.

To increase the latitude and flexibility of this adjustment, a double eccentric effect can be secured by mounting the offset stem 7 in the eccentric sleeve 10, as shown in the modified form set forth in Fig. 4. This sleeve 10 extends downward to the supplementary support 9, the support and the boss 8 being simply drilled larger to receive said eccentric sleeve. The handle 10¹ enables the sleeve to be turned, and thus increase the range of movement of the offset stem.

In the diagrammatic view shown in Fig. 5 the large circle 11 represents the discharge-outlet and the circles 12 the cone. The small circle 13 represents the path of movement of the cone-center about the center of the stem, the radius of the circle representing the extent of the offset. The small circle 14 represents the path of movement of the cone-stem about the center of the eccentric sleeve 10. The cone-circle 12 (shown in full lines) represents the cone in its central position in the opening 3. The dotted circle 12¹ represents the cone in its farthest position to the right and 12² the same to the left.

12³ is the position of the cone when moved transversely to the last-described movement by the combined effect of the cone-stem and eccentric sleeve.

The oil is introduced through the pipe 15,

which may be fed by gravity or any other suitable means which will furnish a practically uniform pressure. The conical point 15' of this pipe terminates adjacent to the cone 5 stem 7, so that the oil will impinge said stem, after which capillary attraction and gravity will cause it to follow the stem to the apex of the cone. The oil is thus exposed to the in-rushing current of air on all sides, and when 10 descending the cone it becomes rapidly attenuated, owing to the increased surface over which it is spread and the impinging air-currents striking it so direct. Before reaching the lower margin of the cone the oil will have 15 been all taken up and the air thoroughly carbureted, after which it will pass into the furnace for combustion. This form of mixing device has been found very efficient, so efficient that the hot portion of the flame or the 20 zone of intense combustion is brought to a distance less than half that found in ordinary burners and with a corresponding increase in calorific efficiency. To provide pure air for a possible excess of oil or "slobberings" due to 25 inaccurate adjustment of the oil-inlet, the by-pass 16 is formed in the mixing-chamber. The upper end of this by-pass begins above the oil-inlet, and the lower end or outlet terminates adjacent to the discharge-opening 3. 30 In operation the oil-pressure is quite small, and the air-current assists in drawing in the oil. The lateral adjustment of the cone 6 is effected, as already described, while the longitudinal adjustment is accomplished by 35 turning the cone-stem up or down in its threaded bearing. It is obvious that if the cone is lowered from the full-line position of Fig. 1 to the dotted-line position in the same figure the area between the cone and edge of 40 the discharge-opening will be greatly increased, while the movement in the opposite direction will have the reverse effect. The longitudinal adjustment of the cone 6 not only regulates the volume of flame, but also

controls its length and enables the hottest 45 portion of the flame to approach or recede from the end of the burner. This longitudinal adjustment in connection with the lateral adjustment of the cone results in such a latitude of movement of the flame that the hot 50 portion thereof can readily be brought to the position on the work in which it will be the most effective, and thus result in a highly efficient burner.

What I claim as my invention, and desire 55 to secure by Letters Patent, is—

1. In a liquid-fuel burner, in combination, a mixing-chamber having an air-inlet and a discharge-opening, an oil-inlet, a cone placed in said discharge-opening with its apex extending inwardly, a vertically-extending offset cone-stem arranged eccentrically with respect to the discharge-outlet for supporting said cone, the cone-stem being located directly in the path of and closely adjacent to 60 the discharge-orifice of the said oil-inlet and thereby constituting means down which the oil flows by gravity upon the apex of said cone, and means for turning said cone-stem for regulating the extent of opening at any 65 desired position in the discharge-opening, substantially as and for the purpose specified.

2. In a liquid-fuel burner, in combination, a mixing-chamber having an air-inlet and discharge-opening, an oil-inlet, a cone arranged in said discharge-opening, a cone-stem for supporting same, said cone-stem serving to conduct the oil from the oil-inlet to said cone, and a by-pass for the air leading 75 from a position in the air-inlet above the oil-inlet to the discharge-outlet at a point below the cone, substantially as and for the purpose specified.

JOSEPH R. RUSSELL.
